CLAIM

The ornamental design for a combined massager with massager controller as shown and described.

DESCRIPTION

FIG. 1 is a bottom view of a massager, showing the new design shown separately for convenience of illustration; FIG. 2 is a top view thereof;

FIG. 3 is a perspective view thereof;

FIG. 4 is another perspective view thereof;

FIG. 5 is a front view thereof;

FIG. 6 is a rear view thereof;

FIG. 7 is a left side view thereof;

FIG. 8 is a right side view thereof;

FIG. 9 is a bottom view of a massager controller, showing the new design shown separately for convenience of illustration;

FIG. 10 is a top view thereof;

FIG. 11 is a perspective view thereof;

FIG. 12 is another perspective view thereof;

FIG. 13 is a front view thereof;

FIG. 14 is a rear view thereof;

FIG. 15 is a left side view thereof; and,

FIG. 16 is a right-side view thereof.
